(57) **CLAIM**

The ornamental design for an electronic device charger, as shown and described.

DESCRIPTION

FIG. 1 is a front perspective view of an electronic device showing my new design;

FIG. 2 is a front elevational view thereof;

FIG. 3 is a rear elevational view thereof;

FIG. 4 is left side elevational view thereof;

FIG. 5 is right side elevational view thereof;

FIG. 6 is a top plan view thereof; and,

FIG. 7 is a bottom plan view thereof.

The broken lines in the Figures show portions of the electronic device charger which form no part of the claimed design. The shade lines in the Figures show contour and not surface ornamentation.

My electronic device charger design is characterized by rounded structural corners and an electronic device placement seat.
